UNITED STATES PATENT OFFICE.

BIRGER LJUNGSTRÖM AND FREDRIK LJUNGSTRÖM, OF STOCKHOLM, SWEDEN, ASSIGNEES TO AKTIEBOLAGET LJUNGSTRÖMS ANGTURBIN, A CORPORATION OF SWEDEN.

ELASTIC-FLUID TURBINE.

1,269,541.

Specification of Letters Patent. Patented June 11, 1918.

Application filed August 8, 1917. Serial No. 185,180.

To all whom it may concern:

Be it known that we, BIRGER LJUNGSTRÖM and FREDRIK LJUNGSTRÖM, subjects of the King of Sweden, residing at Stockholm, Sweden, have invented certain new and useful Improvements in Elastic-Fluid Turbines, of which the following is a specification.

The present invention relates to elastic-fluid turbines and has for its object to provide an improved arrangement for fastening turbine blades to the rotor or blade-carrying member.

For a consideration of what we believe to be novel and our invention, attention is directed to the accompanying specification and the claims appended thereto.

In the accompanying drawing which is illustrative of our invention, Figure 1 is a view illustrating the structure of the blade and blade-carrying member before they are fastened together, Fig. 2 shows the blade mounted on the blade-carrying member; Fig. 3 is a side view of a portion 25 of a blade-carrying member with blades mounted thereon, and Fig. 4 is a top plan view of Fig. 3.

Referring to the drawing, 5 indicates a rotor or blade-carrying member which may 30 take the form of a disk, drum, or ring, for example, and 6 indicates blades mounted thereon. The member 5 is provided with shoulders 7 and a rim 8 upon opposite sides of which are formed concentric ridges or 35 projections 9 which are undercut more or less so that they slope or incline toward the center of the member 5. The amount which they are undercut is exaggerated in the drawings for the purpose of illustration. 40 Between the ridges 9 are concentric grooves 10 which also incline toward the center of member 5. The bases of the buckets are U-shaped, having legs 11 which straddle the rim 8. The inner sides of the legs 11 are 45 formed with ridges 12 and grooves 13 which are complementary to grooves 10 and ridges 9 on rim 8, and slope in the opposite direction.

In assembling the blades on the rim, the 50 bucket base is put over the rim with one leg on each side, as shown in Fig. 1, after which the two legs are pressed together toward the rim, thus bringing the ridges and grooves thereon into locking engagement, 55 as shown in Fig. 2. For this pressing to-

gether a heavy pressure is required and the blade base is displaced radially outward away for the shoulders 7, which obviously will leave a small space between the bottom of the legs 11 and the surfaces of the shoulders 7. To secure a firm and reliable connection this space is filled up so as to prevent the blades from becoming loose. This is preferably done by upsetting the bottoms of the legs 11, as the portions thereof indicated at 14, Fig. 1. After the upsetting operation the appearance is as shown in Fig. 2. Other means for filling such space may be employed, however. For example, the shoulders 7 may be upset, or the space 70 filled in by some other means.

By the above described arrangement, the use of a filling slot is avoided and a solid ring of equally spaced blades results. The assembling of the blades on the blade-carrying member is also much simplified. At the same time, the blades are very firmly fixed in position.

In accordance with the provisions of the patent statutes, we have described the principle of operation of our invention, together with the apparatus which we now consider to represent the best embodiment thereof; but we desire to have it understood that the apparatus shown is only illustrative, and that the invention can be carried out by other means.

What we claim as new and desire to secure by Letters Patent of the United States, is,—

1. In an elastic-fluid turbine, the combination of a blade-carrying member having a rim provided with projections and grooves which slope toward the center of said member, and blades having U-shaped bases which fit over said rim and have complementary projections and grooves sloping away from the center of said member, said projections and grooves on the rim and blade bases interlocking to fasten the blades to the rim.

2. In an elastic-fluid turbine, the combination of a blade-carrying member having a rim, and shoulders at the base of the rim, said rim being provided with projections and grooves which slope toward the center of said member, blades having U-shaped bases which fit over said rim and have complementary projections and grooves sloping away from the center of said member, said

projections and grooves on the rim and 5
blade bases interlocking to fasten the blades
to the rim, and means for filling up the
spaces left between said shoulders and the
radially inner ends of the blade bases.

3. In an elastic fluid turbine, the combination of a blade carrying member having a rim, and shoulders at the base of the rim, said rim being provided with projections 10 and grooves which slope toward the center of said member, and blades having U-shaped bases which fit over said rim and have complementary projections in the

grooves sloping away from the center of 15
said members, said projections and grooves on the rim and blade bases interlocking to fasten the blades to the rim, the radially inner ends of the blade bases being upset against said shoulders to fill the space left between such blade base ends and said 20 shoulders to hold the blades securely in position.

In witness whereof, we have hereunto set our hands this 22nd day of June, 1917.

BIRGER LJUNGSTRÖM.

FREDRIK LJUNGSTRÖM.
